(57) **CLAIM**

The ornamental design for a four lugged lamp socket, as shown and described.

DESCRIPTION

FIG. 1 is a top, front and left side perspective view of a four lugged lamp socket, showing our new design;

FIG. 2 is a top, rear and right side perspective view thereof;

FIG. 3 is a front elevation view thereof;

FIG. 4 is a rear elevation view thereof;

FIG. 5 is a left side elevation view thereof; and,

FIG. 6 is a right side elevation view thereof.

The broken line showing of the environment is for illustrative purposes only and forms no part of the claimed design.
